INCINERATOR

Bruce F. McLouth, Hopkins, Minn., assignor to
Burn-Zol Inc., a corporation of Minnesota
Filed Apr. 25, 1961, Ser. No. 105,412
7 Claims. (Cl. 110—18)

This invention relates to incinerators for burning refuse and the like and more particularly relates to the apparatus for charging the incinerator.

It is not uncommon to construct a refuse-burning incinerator on one side of a building wall and have the charging doors disposed on the other side of the wall with a feed passage going through the wall. In this type of incinerator arrangement, the feed passage will generally have a heat-resisting fire door in the feed passage adjacent the wall. It has been experienced that the heavy metal plates defining the walls of the feed passage in the area between the building wall and incinerator fire pot are exposed to substantial heat because of their close proximity to the fire in the incinerator, and that these heavy metal plates will, as a result of the intense heat, buckle and warp so that they will occasionally need replacing.

With these comments in mind, it is to the elimination of these and other problems that the present invention is directed, along with the inclusion therein of other novel and desirable features.

An object of the invention is to provide a new and improved incinerator charging apparatus of simple and inexpensive construction and operation and which will withstand the high temperatures to which the apparatus is exposed without being damaged by the heat.

Another object of the invention is to provide a novel feed passage construction directing combustion air into the fire pot of the incinerator in such a manner that all portions of the feed passage are cooled to the extent of preventing damage to the feed passage from the intense heat from the fire in the incinerator.

Still another object of my invention is to provide a new and novel feed passage construction through which combustion air is supplied in such a manner as to cool the feed passage walls and to preheat the combustion air as it moves toward the firepot of the incinerator so as to cause improved combustion of the burning materials in the incinerator.

A further object of the invention is to provide an improved and novel incinerator charging feed passage construction including a fire door of extremely rugged construction which will withstand the abuse of constant usage in opening and closing and will retain its capabilities of withstanding the intense heat from the fire pot without the use of fire clay or brick.

These and other objects and advantages of the invention will more fully appear from the following description made in connection with the accompanying drawings wherein like reference characters refer to the same or similar parts throughout the several views and in which:

FIG. 1 is a perspective view of the incinerator in an outdoor location and adjacent a building wall through which the incinerator is charged;

FIG. 2 is a detail section view taken on a vertical plane as indicated approximately at 2—2 in FIG. 1;

FIG. 3 is a detail section view taken approximately at 3—3 in FIG. 2; and

FIG. 4 is a detail section view taken approximately at 4—4 in FIG. 2.

One form of the invention is shown in the drawings and is described herein. As seen in FIG. 1, the incinerator which is indicated in general by numeral 10 is mounted on a suitable base 11 such as a slab of concrete or the like and is disposed in spaced relation with the outer

2

side of a building wall 12. The incinerator 10 has a fire pot 13 with a conventional ash door 14, and a stack 15 of substantially conventional design is provided for the incinerator and may be secured by suitable bracing to the building wall 12. It should be understood that the incinerator 10 may be of the free-standing type suitably braced within itself to eliminate the need for the building wall.

An elongate and open-ended enclosure, indicated in general by numeral 16 is provided for charging the incinerator through the wall 12. The enclosure 16 may if desired be suitably braced and supported from the incinerator itself if the incinerator is of the free-standing type. The enclosure 16 has a pair of telescopically related sections 17 and 18 which extend through the building wall 12, and a feed throat section 19 extending between the wall 12 and the incinerator fire pot. It will be noted that the incinerator fire pot has a feed opening 20 in the side thereof aligned with the opening 21 in the wall 12 to accommodate the feed passage-defining enclosure 16. The enclosure section 17 has a vertically sliding access door 22 therein and extending through a slot 23 in the bottom wall to permit opening and closing of the door 22. The door is suitably guided in channels at the opposite sides of the section 17 and is suspended by rods 24 at the sides of the section 17 and from a cable 25 which is trained over pulleys 26 which are suitably anchored on brackets attached to the building wall 12. The door 22 has a foot pedal 27 or other suitable device to facilitate sliding of the door 22 downwardly when it is desired to open the door.

The section 18 is affixed as by welding to a pair of upright guide channels 28 which are affixed to the wall as by brackets 29. The guide channels 28 guide a hollow air-cooled fire door 30 in vertical movement, into and out of obstructing relation with the feed passage 31. The hollow fire door 30 is also suspended from the cable 25 and is slidable in a slot 32 in the top of enclosure 16 which is defined between the ends of section 18 and throat 19. It will be noted that the bottom wall 18a of section 18 underlies the bottom edge portion of door 30 and overlies the bottom wall 33a of the feed throat section 19.

The door 30 has its upper portion 30a normally disposed at the exterior of the enclosure 16 and has an air inlet opening 34 normally exposed to the atmosphere. The front panel 35 of door 30 has its lower edge spaced from the bottom wall 36 of the door so as to define an air outlet opening 37 closely adjacent the bottom edge of the door and the bottom wall 33a of the feed throat 19. The sidewalls 33b and 33c of the feed throat 19 have large, substantially rectangular air openings 38 disposed closely adjacent the top wall 33d of the feed throat. The sidewalls 33b and 33c are also provided with conduit-defining exterior panels 39 at their outer sides so as to define air flow passages 40 along the exterior surfaces of the sidewall panels 33b and 33c. The passages 40 are open at their lower ends so as to permit air to flow upwardly and then inwardly along and across the top wall 33d.

It should be noted that combustion air is provided only through the feed throat 19 over the grates of the incinerator fire pot and that there is no other source of combustion air.

In operation, when a fire is burning in the incinerator fire pot, the radiant heat from the fire will tend to heat up the fire bricks lining the fire pot and the feed throat 19 and fire door 30. However, the entire feed throat and fire door are cooled by the combustion air flowing inwardly through the hollow fire door 30 and hollow sidewalls of the feed throat. The air will flow in the direction of arrows *a* downwardly through the door 30 and will cool the front panel 35 of the door and thence the air will flow

outwardly through the opening 37 and across the bottom wall 33a of the feed throat so as to cool the bottom wall. Combustion air also flows upwardly in the direction of arrows b through the air conduits 40 and the feed throat sidewalls and inwardly through the openings 38 and across the top wall 33d of the feed throat. By this cooling, effected by the inflow of combustion air, the entire feed throat and fire door assembly is cooled sufficiently to prevent any damage or warping or buckling to these portions of the structure which are continuously exposed to the radiant heat of the fire in the fire pot. Furthermore, it will be noted that when additional refuse or fuel is to be placed in the incinerator, the access door 22 is opened by pushing down on the lever 27 whereupon the fire door 30 moves upwardly into open position. Because of the constant cooling of the fire door 30 there will be no scorching of the wall as the fire door is moved upwardly into closely spaced confronting relation therewith. Likewise, when the door 30 is in its closed position, the building wall 12 and the enclosure sections 17 and 18 and the access door 22 are all protected from the intense heat of the fire.

It should be pointed out that the combustion and cooling air cools the exterior surfaces of the enclosure 16 sufficiently to minimize the possibility of a person being burned and so that the temperature of the exterior of the feed passage 16 is continuously unobjectionable. This is particularly important when the feed passage 16 is fully supported on an incinerator of the free-standing type wherein the building wall is not used. In these conditions the length of the feed passage may be somewhat decreased.

It should also be noted that the fire door 30 may take various forms. For instance the fire door may in certain instances be divided into upper and lower sections, the uppermost of which will move upwardly and the lowermost of which will move downwardly to open the feed passage 31. In this situation one of the upper or lower sections of the fire door will move in a similar direction to the access door 22. It will be understood that such upper and lower sections of the fire door will cooperatively provide an air conduit operating to supply air in a manner substantially identical to fire door 30. It should be understood that because the major portion of the refuse will be disposed and burned in the lower portion of the firepot 13 below the feed passage, the lowermost plate or wall 33a will be subjected to substantially less heat than the other walls 33b, 33c and 33d. In certain instances it is therefore permissible to position the air outlet opening in the fire door at a location intermediate the upper and lower ends of the fire door; this location of the air outlet opening may be desirable when a two-part fire door having upwardly and downwardly movable upper and lower sections is used and wherein the upper and lower sections of the fire door both take in combustion air from the exterior of the feed passage at their upper and lower edges respectively; the combustion air being supplied through such an air outlet opening disposed intermediate the upper and lower walls of the feed passage will cause sufficient cooling of the fire door and will also cause sufficient turbulence of the combustion air being supplied in the feed passage as to cause the combustion air to sweep across and adequately cool the lowermost wall of the feed passage.

It will be seen that I have provided a novel apparatus through which the incinerator is charged and which is constructed simply but in such a manner that the entire feed throat and fire door are cooled by inwardly flowing, over fire combustion air as to prevent any buckling, warping or other damage due to heat, to the feed throat or fire door.

It will, of course, be understood that various changes may be made in the form, detail, arrangement and proportion of the parts without departing from the scope of the invention which consists of the matter described herein and set forth in the appended claims.

What is claimed is:

1. An incinerator, comprising means defining a fire pot with a feed opening in the side thereof, an elongate feed throat having an inner end communicating with said feed opening and an outer end, a fire door obstructing the feed throat at said outer end, means mounting said door for movement out of obstructing relation with the feed throat, said feed throat having first and second walls disposed opposite each other and also having third and fourth walls disposed opposite each other and rigidly affixed to said first and second walls, each of said walls having interior and exterior sides, each of said first and second walls having an elongate air opening therethrough adjacent said third wall and extending along said third wall, enclosure means affixed to the exterior sides of each of said first and second walls and cooperating therewith to define air conduits with air inlets adjacent said fourth wall and directing combustion and cooling air along the exterior sides of said first and second walls for cooling the same and also directing the air through said air openings and across the interior side of said third wall, said door being hollow and having a metal plate facing the outer end of the feed throat, the door having one edge portion disposed at the exterior of the feed throat and having an air intake opening in said one edge portion, and said metal plate of the door having an elongate outlet opening adjacent the fourth wall of the feed throat and extending along said fourth wall to permit air to be drawn inwardly through said air intake opening and to flow through the door for cooling said plate and across the interior side of the fourth wall, whereby the combustion air cools the feed throat and door to prevent warping thereof.

2. An incinerator, comprising means defining a fire pot with a feed opening in the side thereof, an elongate box-like feed throat having an inner end communicating with said feed opening and an outer end, an air cooled fire door obstructing the outer end of the feed throat and having an inner panel facing inwardly of the feed throat, said door having a hollow interior through which air moves across said panel, means mounting the feed door for movement out of obstructing relation with the feed throat, the feed throat having first and second walls disposed opposite each other and having third and fourth walls disposed opposite each other and rigidly connected to said first and second walls, said first and second walls having apertures therein and also having means directing combustion and cooling air along said first and second walls and through the apertures and across the third wall of the feed throat, said door having an air intake opening at the exterior of the feed throat and an air delivery opening facing inwardly of the feed throat adjacent the fourth wall and directing air across the fourth wall.

3. An incinerator, comprising means defining a fire pot with a feed opening in the side thereof, a feed throat having an inner end communicating with said feed opening and having an outer end, the feed throat having top and bottom walls and also having a pair of upright hollow air-cooled sidewalls affixed to said top and bottom walls, the hollow sidewalls having open lower edge portions to receive combustion and cooling air and having closed upper end portions, said sidewalls having inner panels with air outlets adjacent the top wall to direct the combustion and cooling air inwardly across the top wall, an upright air-cooled hollow door at the outer end of the feed throat, means mounting the door for movement out of and into obstructing relation with the feed throat, the door having an upper portion at the exterior of the feed throat and having an opening in said upper portion to receive combustion and cooling air, the door having an inner panel facing the outer end of the feed throat and said panel having an air outlet adjacent said bottom wall to direct combustion and cooling air inwardly across the bottom wall, whereby the combustion air supplied through the sidewalls and fire door provides continuous cooling

for the entire feed throat to prevent damage thereto due to heat from the fire pot.

4. In combination, a building wall having an enlarged opening therein and having inner and outer sides, an incinerator spaced from the outer side of the building wall and including a fire pot with a feed opening in the side thereof and aligned with the opening in the building wall, enclosure means defining a feed passage extending through the opening in the building wall and having an inner end communicating with the feed opening of the fire pot and also having an outer end at the inner side of the building wall, an access door in the feed passage at the outer end thereof, means mounting said access door for movement into and out of obstructing relation with the feed passage, a fire door in the feed passage and disposed between the outer side of the wall and the fire pot, means mounting the fire door for movement out of and into obstructing relation with the feed passage, the fire door being hollow to permit air flow therethrough, the door having an inner panel generally facing the fire pot, the fire door having opposite edge portions, one of said edge portions being open to receive air therein, said panel having an outlet opening adjacent the other edge portion of the door, the passage-defining enclosure means having an opening therein receiving said open edge portion of the door therethrough to permit atmospheric air to enter the door and flow therethrough and into the feed passage whereby to cool the fire door and prevent exposing of the wall to heated combustion.

5. In combination, a building wall having an enlarged opening therein and having inner and outer sides, an incinerator spaced from the outer side of the wall and including a fire pot with a feed opening therein, and aligned with the opening in the building wall, enclosure means defining a feed passage extending through the opening in the building wall and having an inner end communicating with the feed opening in the fire pot and also having an outer end at the inner side of the building wall, an access door in the feed passage at the outer end thereof, means mounting said access door for movement into and out of obstructing relation with the feed passage, a fire door in the feed passage and disposed between the outer side of the wall and the fire pot, the passage-defining enclosure means having an opening adjacent the top of the fire door and receiving the top of the fire door therethrough, means slidably mounting the fire door for vertical sliding movement out of and into obstructing relation with the feed passage and into confronting relation with the wall above the feed passage, the fire door being hollow to permit air flow therethrough, the door having an inner panel facing the fire pot and having opposite upper and lower edge portions, the upper edge portion of the door being open to receive air therein and said panel having an outlet opening therein adjacent the lower edge of the door to direct combustion air downwardly through the door and into the feed passage to the fire pot whereby to cool the door to protect said wall when the door is shifted into and out of feed-passage-obstructing positions.

6. A feed throat for attachment to an incinerator sidewall at the feed opening therein, said feed throat having a substantially rectangular shape and including a pair of upright air-cooled sidewalls disposed opposite each other, each of said sidewalls having thickness and an open interior extending transversely of the thickness of the sidewall, said feed throat also including horizontal top and bottom walls opposite each other and affixed to said air-cooled sidewalls to cooperate therewith in

defining a feed throat enclosure, the enclosure having an inner end to be disposed adjacent the incinerator sidewall and an outer end, an upright air-cooled fire door in obstructing relation with the outer end of the enclosure, means on said enclosure and mounting said door for movement out of obstructing relation with the outer end of the enclosure, said door having thickness and having an open interior extending transversely of the thickness of the door, said open interior of the door being 10 unobstructed in a vertical direction to permit passage of air vertically therethrough for cooling the door, said air-cooled sidewalls and said fire door having air outlets communicating with said open interiors and with the enclosure, each of said outlets being disposed adjacent 15 a respective one of said horizontal walls to direct air thereacross for cooling, said air-cooled sidewalls and fire door also having air inlets respectively disposed remotely in a vertical direction from said outlets and said air inlets of the air-cooled sidewalls and fire door respectively communicating between the open interior of 20 said sidewalls and said door and the exterior of the enclosure whereby to supply combustion and cooling air to move vertically through said air-cooled sidewalls and fire door and horizontally across said top and bottom walls for cooling the entire feed throat and fire door.

7. A feed throat for attachment to an incinerator sidewall at the feed opening therein, said feed throat having a substantially rectangular shape and including a pair of air-cooled upright sidewalls disposed opposite each other and having upright passages permitting cooling air to move upwardly therethrough, said feed throat also including top and bottom walls opposite each other and affixed to said air-cooled upright sidewalls to cooperate therewith in defining a feed throat enclosure the enclosure having an inner end to be disposed adjacent the firepot and having an outer end, an upright air-cooled fire door in obstructing relation with the outer end of the enclosure, means mounting said door on the enclosure for movement out of obstructing relation with the outer end of the enclosure, said door having an upright air passage therein with an air inlet and an air outlet widely spaced from each other in a vertical direction thereby permitting downward movement of the air through the passage in the door for cooling the door, the upright passages of said air-cooled sidewalls having air outlets opening inwardly of the enclosure and disposed adjacent said top wall and having air inlets disposed remotely from said outlets and adjacent the bottom wall and opening to the exterior of the enclosure, and 30 said air outlet of the passage in the door opening inwardly of the enclosure and being disposed adjacent the bottom wall to direct air across the bottom wall and effect cooling thereof, the air inlet of the passage in the door opening to the exterior of the enclosure adjacent the top wall, whereby to cause combustion and cooling air to move upwardly through the air-cooled sidewalls and downwardly through the fire door and inwardly across the top and bottom walls for cooling the entire feed throat and fire door.
